DESIGN FOR A COMBINED TYPEWRITER AND DESK SUPPORT THEREFOR

Frederic S. Grover, Rochester, N. Y., assignor to
International Business Machines Corporation,
New York, N. Y., a corporation of New York

Application November 7, 1946, Serial No. 134,600

Term of patent 14 years

(Cl. D64—11)

To all whom it may concern:

Be it known that I, Frederic S. Grover, a citizen of the United States and a resident of Rochester, county of Monroe, and State of New York, have invented a new, original, and ornamental Design for a Combined Typewriter and Desk Support Therefor, of which the following is a specification, reference being had to the accompanying drawing, forming part thereof. The figure is a front perspective view of a combined typewriter and desk support therefor, showing my new design. The back of the same, not shown, is substantially plain, except for the shelf which has a uniform width and extends across the back substantially coextensive therewith.

I claim:

The ornamental design for a combined typewriter and desk support therefor, substantially as shown and described.

FREDERIC S. GROVER.
